UNITED STATES PATENT OFFICE.

LOUIS T. REICHERS, OF ARLINGTON, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed May 8, 1922. Serial No. 559,127.

To all whom it may concern:

Be it known that I, LOUIS T. REICHERS, a citizen of the United States, residing in Arlington, in the county of Hudson and 5 State of New Jersey, have invented certain new and useful Improvements in Type-writing Machines, of which the following is a specification.

This invention relates to means for reducing the noise produced by the striking of types against the platen of a typewriting machine.

An object of the invention is to produce a front-strike action of simple and inexpensive construction without departing to any 15 extent from the general construction of type-actions heretofore employed.

The invention resides in improved means for stopping the movement of the type-bar just as the type reaches the printing position, and may comprise an extensible and collapsible device, such as a pair of pivotally joined links forming a toggle, one 20 of these links being pivoted to the type-carrying arm of the type-bar, and the other link being pivotally connected to the up-standing arm of a bell-crank lever which is actuated by a key-lever, the bell-crank lever being connected independently of the 25 type-links to the type-bar for actuating the latter, the toggle-links being of such length that when stretched from a collapsed to an extended position they will be effective to stop the movement of the type 30 just as it reaches the printing position. A feature of the invention is the employment of a spring to prevent the toggle-links becoming locked on dead center.

Other features and advantages will hereinafter appear.

In the accompanying drawings,

Figure 1 is a side elevation with parts in section, and shows two type-actions embodying the present invention, in one of 45 which the parts are in the normal position, and in the other of which the parts are in the operated position, with the type at the printing point on the platen.

Figure 2 is a partial front elevation showing the arcuate arrangement of the type-bars in the type segment, and means, forming a feature of the present invention, for guiding the upstanding arms of the bell-crank levers to prevent the pull of the move-

ment-limiting toggle-links from deflecting 55 these arms of the bell-crank levers laterally.

In the embodiment of the invention shown in the drawings, for each of the type-actions a type-key 1 is carried by the forward end of a depressible key-lever 2, 60 pivoted at its rear end on a rod 3, and the key-lever 2 is raised from depressed to normal position by a compressible restoring spring 4. The key-lever 2 carries a stud 5 engaging in a curved slot 6 in the end 65 of a short normally upwardly-inclined front arm 7 of a bell-crank lever pivoted upon a transverse rod 8, the slot 6 being curved upwardly towards its open end to produce an easier initial key-action, together with 70 accelerated movement of the bell-crank lever, this slot being on the whole substantially radial to the pivot point 8 of the bell-crank lever. The bell-crank lever has a long upstanding arm 9, the upper end 75 of which is pivoted at 10 to the forward end of a bent link 11, which at its rear end curves upwardly and is pivotally connected at 12 to a normally rearwardly and slightly downwardly extending short arm 13 80 of an upwardly and rearwardly swinging type-bar having a long and normally forwardly-extending arm 14 carrying a type-head 15 having types 16 to print upon the front of a platen 17. All the type-bars 85 are pivoted, by means of pivot-holes therethrough, on an arcuate fulcrum-forming wire 18 carried by a type-bar segment 19 provided with slots 20 for guiding the type-bars. The long upstanding lever-arms 9 of 90 the bell-crank levers become longer and longer towards the sides of the machine and are bent inward more and more at 21, so that the upper inwardly-bent ends 22 of these lever-arms are radial to the arcuate 95 type-bar segment 19, to correspond with the arcuate arrangement of the type-bars, as is commonly the case in front-strike type-writing machines.

When a type-key 1 is struck and depressed 100 by the finger of the typist, the connections from the key-lever to the type-bar, comprising the bell-crank having the lever-arms 7 and 9, and the link 11, swing the type-carrying arm 14 of the type-bar from its normally substantially horizontal position, occupied in one of the type-actions shown in Figure 1, rearwardly to the printing posi-

tion of the types 16, as is shown in the other type-action illustrated in Figure 1. The construction and arrangement of the lever and link mechanism is such that the movement of the type-head 15 will be accelerated as it approaches the printing point on the platen 17, such accelerated movement being largely due to the downward and forward travel of the key-lever stud 5 along the curved slot 6 in the short lever-arm 7 of the bell-crank lever. The restoring spring 4 for the key-lever 2 will be effective to return the type-bar from the printing position to normal position, this return movement being assisted by the weight of the type-bar and its type-head 15. The type-action, as so far described, does not greatly differ from type-actions which have been heretofore employed.

Before proceeding further, it should be noted that the type-action as so far described, is entirely effective for typing operations, and, in this respect, may be considered a complete type-action. However, it is to be noted that the acquired momentum of the moving parts of the type-action, and particularly of the long lever-arm 14 of the type-bar and especially of the type-head 15, the impact of which is utilized to cause the types 16 to print, will produce a comparatively loud clacking noise, due to the hammer-like blow received by the platen 17, and this noise is objectionable, especially in view of the high speed at which the machine is usually operated.

According to the present invention, positively-acting means are provided for checking or stopping the further movement of the type-bar, type-head 15 and types 16 carried thereby just about at the position or just preceding the position reached at which a type 16 will come in contact with the printing surface of the platen 17, in the absence of a work-sheet thereon, so that when a work-sheet (not shown) is in place upon the platen the work-sheet and usual ink-ribbon (not shown) will receive the printing impact of a type 16, the hammer-like blow of the types 16 being expended upon the work-sheet and not being to any extent communicated to the platen upon which the work-sheet is held at the typing position.

In the particular embodiment of the invention shown in the drawings, such means comprise a pair of toggle-links 23 and 24 pivoted together at 25, the other end of the upper toggle-link 23 being pivoted at 26 to the type-carrying arm 14 of the type-bar at a point comparatively near to the type-head 15 and considerably nearer to the type-head than to the pivot point 18 of the type-bar, and the other end of the lower toggle-link 24 being pivoted to the upstanding arm 9 of the bell-crank lever at the upper end thereof at the pivot point 10 for the type-

actuating link 11. In the normal position of the several parts of the type action, the toggle-links 23 and 24 are in collapsed condition and are folded near to each other with the lower toggle-link 24 extending substantially horizontally rearward from its pivot point 10 on the upstanding arm 9 of the bell-crank lever, as is shown by one of the type-actions illustrated in Figure 1. When a type-key 1 is depressed to swing the long type-carrying arm 14 of the type-bar upwardly and rearwardly, by means of the operating connections hereinbefore described, including the bell-crank lever and link 11, the upward and rearward movement of the type-carrying type-bar arm 14 together with the forward and slightly downward movement of the pivot point 10 on the upstanding bell-crank arm 9, will expand or straighten out the toggle-joint formed by the pivotally connected toggle-links 23, 24, as is shown by the other type-action illustrated in Figure 1. The toggle-links 23 and 24 are of the proper length so as to become fully expanded or straightened into alignment with each other just at the moment of time and just at the position reached in the typing movement of the types 16 at which one of these types, depending upon the case-shift position of the platen 17, would come into contact, or not quite into contact, with the printing surface of the platen 17, as is shown by the raised type-bar in Figure 1. Therefore, it will be evident that when work-sheets (of which, of course, there may be one or more) are upon the platen, the type 16 which is to do the printing will be still moving rearwardly when it strikes against the usual ink-ribbon, and that the work-sheet (or sheets) held by the platen will receive from the type a blow to produce printing pressure of the type, and that the typing movement of the type will be arrested in time to prevent a noise-producing hammer blow being delivered to the printing surface of the platen, this blow being received by the interposed work-sheet, and the printing surface of the platen receiving only the pressure caused by the printing upon the work-sheet. After the printing of one of the types 16 upon the work-sheet, further rearward movement of the type-carrying type-bar arm 14, and consequently of the types 16, is positively prevented by the straightened or stretched toggle-links 23 and 24, which operate to lock the type-action as soon as printing has been effected, so as to prevent further rearward movement of the type-bar arm 14, type-head 15 and types 16 carried thereby.

In order to prevent the accidental locking of the toggle-links 23 and 24 on dead center, against return movement, and also to avoid the possibility of these links collapsing or folding in the wrong direction,

that is, forwardly instead of backwardly and downwardly, a spring 27 is provided to initiate the correct or rearward and downward folding movement of the toggle-links 23 and 24. The spring 27 is shown as a bowed or substantially U-shaped retractile spring which may be formed of suitable spring wire, and is shown as bowed or bent at its middle towards the pivot point 26 5 of the upper toggle-link 23, and at one of its ends is pivotally connected at 28 to the type-carrying type-bar arm 14, and at its other end is pivotally connected at 29 to the upper toggle-link 23, so that the spring 27 10 will be effective to break the lock of the toggle-links in their aligned or stretched condition shown in Figure 1, to permit free return movement of the type-bar, and the spring 27 also will assist in such return 15 movement.

In order to prevent the springing or lateral deflection of the upstanding lever arms 9 of the bell-crank levers due to their angular pull upon the straightened toggle-links 23 and 24, particularly at the sides of the machine, an arcuate guide-bar 30, provided in its forward edge with rearwardly-extending vertical guide-slots 31, to receive the upstanding bell-crank arms 9, is 20 mounted on the machine below and to the front of the type-bar segment 19, as shown in the drawings, in such position that the bell-crank arms 9 will engage in the guide-slots 31 just below the lateral bend 21 25 therein.

An inspection of the drawings, in connection with the foregoing description, will make it clear that the movement limiting device for the type-carrying arm 14 of the type-bar, comprising the toggle-links 23 and 24, plays no part whatever in swinging the type-bar to the typing position, that is to say, these links do not communicate any movement from the bell-crank lever to the type-bar; nor, on the other hand, do these toggle-links hamper or interfere with the swinging movement of the type-bar as the type-bar swings to the printing point. However, these links do positively limit or 30 prevent any further movement of the type-bar after printing has been effected. In this connection, it is to be further noted that the toggle-links 23 and 24 form a continuous or unbroken connection to the type-carrying arm of the type-bar for positively limiting the throw of the type-bar, the type-bar not being permitted to strike against anything, the movement of the type-bar being stopped by the stretching of the pivoted links 23 and 24 into alignment, at 35 which point, of course, the limit of extension is reached, and the rearwardly-swinging type-bar is thus brought to a stop noiselessly. The final result is that the momentum of the swinging type-bar and type-

head 15 carried thereby is left free to be expended to the extent necessary for effecting the typing operation upon a work-sheet, but is not further left free to be expended in striking a noise-producing blow 70 upon the platen.

Variations may be resorted to within the scope of the invention, and portions of the improvements may be used without others.

Having thus described my invention, I 75 claim:

1. A noise-reducing type-action for type-writing machines, comprising, in combination with a platen, a swinging type-bar, means including a type-key for swinging 80 the type-bar to printing position, said means including a part of the type-action which has a receding movement from the normal position of the type-bar as the type-bar recedes from its normal position and swings 85 to printing position, and means to prevent further movement of the type-bar after printing has been effected, comprising an extensible and collapsible device connected to the type-bar and to said receding part of the type-action, further movement of the type-bar after printing being prevented by reason of the oppositely-moving type-bar and said receding part of the type-action causing said device to reach its limit of 90 95 extension.

2. A noise-reducing type-action for type-writing machines, comprising, in combination with a platen, a swinging type-bar, means including a type-key for swinging 100 the type-bar to printing position, said means including a part of the type-action which has a receding movement from the normal position of the type-bar as the type-bar recedes from its normal position and swings to printing position, and means to prevent further movement of the type-bar after printing has been effected, comprising a plurality of pivotally-joined links 105 pivotally connected to the type-bar and to said receding part of the type-action, said links being of such length as to be fully extended by the oppositely moving type-bar and said receding part of the type-action when the type on the type-bar has reached the printing position.

3. A noise-reducing type-action for type-writing machines, comprising, in combination with a platen, a swinging type-bar, means including a type-key for swinging 110 the type-bar to printing position, said means including a part of the type-action which has a receding movement from the normal position of the type-bar as the type-bar recedes from its normal position and swings to printing position, and means to prevent further movement of the type-bar when printing by the type has taken place, comprising a pair of toggle links, one of 115 which is directly pivotally connected to the 120 125 130

type-carrying arm of the type-bar and the other of which is directly pivotally connected to said receding part of the type-action, said links being of such length as 5 to be fully straightened with their three pivot-points in line in the printing position of the type carried by the type-bar.

4. A noise-reducing type-action for a front-strike typewriting machine, comprising, in combination with a platen, a pivoted type-bar having a long rearwardly-swinging type-carrying arm, and having at the other side of its pivot a short actuating arm, a bell-crank-lever pivoted below and forwardly of the pivot of the type-bar, and having a long upstanding arm and a short front arm, a link pivotally connecting the long upstanding arm of the bell-crank-lever to the short actuating arm of the type-bar, a de- 10 pressible key-lever for actuating the latter to swing the type-bar to printing position, and means for preventing movement of the type beyond the printing position thereof, comprising a pair of toggle-links, one of 15 which is pivotally connected to the type-carrying arm of the type-bar, and the other of which is pivotally connected to the upstanding arm of the bell-crank-lever, said toggle-links being of such length as to be 20 straightened into alignment in the printing position of the type, and a spring tending to collapse the toggle-links downwardly 25 away from dead center as the type-bar returns from the printing position to normal position.

5. A noise-reducing type-action for a front-strike typewriting machine, comprising, in combination with a platen, a pivoted type-bar having a long rearwardly-swinging type-carrying arm, and having at the other side of its pivot a short actuating arm, a bell-crank-lever pivoted below and forwardly of the pivot of the type-bar, and having a 30 long upstanding arm and a short front arm, a link for actuating the type-bar pivotally connecting the long upstanding arm of the bell-crank-lever to the short actuating arm of the type-bar, a de- 35 pressible key-lever connected to the short front arm of the bell-crank-lever, for actuating the latter to swing the type-bar to printing position, means for preventing movement of the type beyond the printing position thereof, comprising a 40 pair of toggle-links, one of which is pivotally connected to the type-carrying arm of the type-bar, and the other of which is pivotally connected to the upstanding arm of the bell-crank-lever at the 45 point thereon at which said link for actuating the type-bar is connected, and a retractile spring connected to the type-carrying arm of the type-bar and to the adjacent toggle-link for moving said toggle-links downwardly away from their dead center as the type-bar returns from the printing position to its normal position, and for overcoming 50 the tendency of the links to overthrow at the toggle joint when the links are moved to their extended position.

6. A noise-reducing type-action for a front-strike typewriting machine, comprising, in combination with a platen, a pivoted type-bar having a long rearwardly-swinging type-carrying arm, and having at the other 55 side of its pivot a short actuating arm, a

bell-crank-lever pivoted below and forwardly of the pivot of the type-bar, and having a long upstanding arm and a short front arm, a link pivotally connecting the long upstanding arm of the bell-crank-lever to the short actuating arm of the type-bar, a de- 60 pressible key-lever connected to the short front arm of the bell-crank-lever, for actuating the latter to swing the type-bar to printing position, means for preventing movement of the type beyond the printing position thereof, comprising a pair of toggle-links, one of which is pivotally connected to the type-carrying arm of the type-bar, and the other of which is pivotally connected to the upstanding arm of the bell-crank-lever, said toggle-links being of such length as to be 65 straightened into alignment in the printing position of the type, and a spring tending to collapse the toggle-links downwardly 70 away from dead center as the type-bar returns from the printing position to normal position.

7. A noise-reducing type-action for a front-strike typewriting machine, comprising, in combination with a platen, a pivoted type-bar having a long rearwardly-swinging type-carrying arm, and having at the other side of its pivot a short actuating arm, a bell-crank-lever pivoted below and forwardly of the pivot of the type-bar, and having a long upstanding arm and a short front arm, a link for actuating the type-bar pivotally connecting the long upstanding arm of the bell-crank-lever to the short actuating arm of the type-bar, a de- 75 pressible key-lever connected to the short front arm of the bell-crank-lever, for actuating the latter to swing the type-bar to printing position, means for preventing movement of the type beyond the printing position thereof, comprising a pair of toggle-links, one of 80 which is pivotally connected to the type-carrying arm of the type-bar, and the other of which is pivotally connected to the upstanding arm of the bell-crank-lever, said toggle-links being of such length as to be straightened into alignment in the printing position of the type, and a spring tending to collapse the toggle-links downwardly 85 away from dead center as the type-bar returns from the printing position to normal position.

8. In a front-strike typewriting machine, the combination with a system of type-actions comprising swinging type-bars pivoted on the machine in an arc, key-levers, and type-bar-actuating connections between the key-levers and the type-bars, said connections including levers having upstanding lever-arms connected to the type-bars, of an 90

- extensible and collapsible device for each type-action connected to said upstanding arm and to the type-carrying arm of the type-bar for limiting the throw of the latter 5 in its typing movement, and guiding means for said upstanding lever-arms to prevent them from being deflected laterally by reason of the angular pull thereon of said device.
- 10 9. In a front-strike typewriting machine, the combination with a system of type-actions comprising swinging type-bars pivoted on the machine in an arc, bell-crank levers pivoted in horizontal alignment below and 15 forwardly of the type-bar pivots and having upstanding lever-arms, key-levers connected to the bell-crank-levers to swing the upstanding lever-arms forwardly when the key-levers are depressed, and links connecting 20 the upstanding lever-arms of the bell-crank-levers to the type-bars to actuate the latter, of an extensible and collapsible device for each type-action comprising links connected to the upstanding lever-arm of 25 the bell-crank-lever and to the type-carrying arm of the type-bar for limiting the throw of the type-bar in its typing movement, and means to prevent the angular pull of said devices from laterally deflecting the up- 30 standing lever arms of the bell-crank levers comprising an arcuate guide-plate having therein guide-slots for the upstanding lever-arms of the bell-crank levers.
10. A type-action for a front-strike type- 35 writing machine, comprising a swinging type-bar, a key-lever, connecting means between the key-lever and the type-bar to actuate the latter, including a stud on the key-lever, and further including a lever having 40 an arm provided with a curved slot in which the stud works, said slot being curved in such manner as gradually to accelerate the movement communicated by the key-lever to said slotted lever, the slotted lever thereby 45 correspondingly accelerating the movement of the type-bar as it swings the type to the printing point, and means for limiting the throw of the type-carrying arm of the type-bar as it swings to the printing position 50 comprising an extensible and collapsible device connected to the type-carrying arm of the type-bar and to a movable part of said connecting means relatively to which said arm has a receding movement as it swings 55 to the typing position.
11. A type-action for a front-strike type- 60 writing machine, comprising a swinging type-bar, a bell-crank lever having a long arm connected to the type-bar to swing the latter to the typing position and having a short arm provided with a curved substantially radial slot, a key-lever, a stud on the key-lever projecting into said slot, said slot being so curved as to impart a gradually-increasing accelerated movement to the bell- 65 crank-lever for correspondingly accelerating the movement of the type-bar as it swings to the typing position, and means for limiting the throw of the type-carrying arm of the type-bar as it swings to the typing position comprising links pivotally connected to the type-carrying arm of the type-bar and to said upstanding arm of the bell-crank-lever.
12. In a noise-reducing type-action for a typewriting machine, in combination, a type-action including a pivoted type-bar arm, and means for limiting the printing stroke of said arm, comprising pivotally connected links with the extremities pivoted to said type-bar arm adjacent its free end and to another moving part of the type-action; said links, during the printing stroke, being extended to the limit, and thereafter being effective to stop the movement of said arm.
13. In a noise-reducing type-action for a typewriting machine, in combination, a type-action including a pivoted type-bar arm, means for limiting the printing stroke of said arm, comprising pivotally connected links with the extremities pivoted to said type-bar arm adjacent its free end and to another moving part of the type-action; said links, during the printing strike, being extended to the limit, and thereafter being effective to stop the movement of said arm, and spring means connected between the type-bar arm and its adjoining link to overcome the tendency of the links to overthrow at the joint when the same are moved to the extended position, and also to effect breakage of the toggle joint when the links have reached dead center for assisting the return movement of said type-bar arm.
14. In a typewriting machine, in combination, a platen, a pivoted arm carrying a type-bar to coact with the platen, a key-lever to actuate the type-bar, an operative connection between said arm and said key-lever for imparting movement to the latter from the former to effect printing, and toggle-links pivoted to said bar and to a movable part of said operative means and extended to limit the printing stroke of said arm independently of said platen.
15. In a typewriting machine, in combination, a platen, a pivoted arm carrying a type-bar to coact with the platen, a key-lever to actuate the type-bar, an operative connection between said arm and said key-lever for imparting movement to the latter from the former to effect printing, toggle-links pivoted to said bar and to a movable part of said operative means and extended to limit the printing stroke of said arm independently of said platen, and spring means mounted between the type-bar arm and one of said links to prevent the overthrow thereof at the pivoted joint and to

impart initial return movement to said arm after the printing stroke.

16. A noise-reducing typewriting machine, comprising, in combination with a platen, a type-action including a pivoted arm carrying a type-bar, a link pivoted to said arm adjacent its free end, and a link pivoted to another moving part of the type-action, said links pivoted together as a toggle and when 10 extended arresting the printing stroke movement of the type-bar to prevent a noise-producing hammer blow being delivered to the printing surface of the platen, and means carried between the type-bar arm 15 and one of said links to prevent overthrow of the toggle joint.

17. A noise-reducing type-action for a front-strike typewriting machine, in combination with a platen, an arm carrying a

type-bar and pivotally mounted therebelow 20 for rearward swinging from a normally disposed substantially horizontal position to a relatively vertical position for effecting printing at the platen, operating means, including a key-lever, to swing said arm, and 25 toggle-links pivoted to said arm and to a movable part of said operating means and acting when extended to determine the printing stroke of said bar, and means carried between the type-bar and said links to 30 prevent overthrow thereof and also to prevent the latter from becoming locked on dead center when the same are extended to limit the printing stroke.
